UNITED STATES PATENT OFFICE.

JOSEPH PHILANDER HASTY, OF BELLEVILLE, KANSAS.

SWITCH-STAND.

1,258,678.

Specification of Letters Patent. Patented Mar. 12, 1918.

Application filed June 5, 1917. Serial No. 172,917.

To all whom it may concern:

Be it known that I, JOSEPH P. HASTY, a citizen of the United States, residing at Belleville, in the county of Republic and State of Kansas, have invented a new and useful Switch-Stand, of which the following is a specification.

The present invention appertains to switch stands or switch throws, and aims to provide a novel and improved device of that character which can be used either as a "single" switch stand or "three-way" switch stand.

Another object of the invention is to provide a novel means in a switch stand for transmitting the power, in order that the switch can be readily actuated by hand in a most effective manner.

Another object is the provision of a switch stand wherein the working parts are protected from the elements. A still further object is the provision in a switch stand of the nature indicated, of novel means for controlling and locking the rotation of the operating shaft.

It is also the object of the invention to provide a switch stand having the characteristics above noted, and which is comparatively simple, compact and inexpensive in construction, as well as being thoroughly practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is an elevation of the switch stand, portions being broken away.

Fig. 2 is a vertical section taken on the line 2-2 of Fig. 1.

Figs. 3 and 4 are sectional details taken on the respective lines 3-3 and 4-4 of Fig. 2.

Fig. 5 is a diagrammatical view of the cam, illustrating the periphery thereof laid out flat.

The numeral 1 designates the upright

body or stand proper, which is constructed of suitable metal, and which has a suitable base 2 adapted to be secured upon the ties or other foundation, said body 1 being provided with a chamber or cavity 3 in the lower portion thereof opening downwardly to house some of the working parts and protect them from the elements. The upper end of the body 1 is provided with an annular outstanding flange 4, and a vertical shaft or staff 5 is journaled for rotation through the upper portion of the body 1 and projects downwardly within the chamber 3. The upper end of the shaft 5 carries a suitable signal 6.

As a means for transmitting the motion from the actuating shaft 5, a cylindrical cam 7 is secured upon the lower portion of said shaft within the chamber 3, and is provided with a circumferential cam groove 8, provided with a portion 9 extending through substantially one half of a circle and disposed in a common plane at right angles with the shaft 5, said groove 8 having an offset cam portion 10 also extending through substantially one half of a circle. The lower end of the cam 7 is journaled or swiveled through a strip or bar 11 terminally secured to the base 2 and extending across the mouth of the chamber 3. The strip 11 is provided adjacent to its opposite edges with upstanding bearings 12 to which are pivoted the elbows of bell crank levers 13. Said levers have depending arms to which links or rods 14 are connected, and said rods are connected in any suitable manner with the switch points. When two levers 13 are employed, the switch stand is of the "three-way" type for operating a double switch, but when a single switch only is operated, one of the levers 13 and corresponding rod or link 14 can be eliminated. The upper arms of the levers 13 carry rollers 15 working in the cam groove 8 and disposed diametrically opposite to one another. Thus, as the shaft 5 is rotated, one of the rollers 15 will work in the portion 9 of the groove 8, while the other will work in the cam portion 10. One lever 13 is thus held stationary, while the other lever 13 whose roller 15 works in the portion 10 of the groove 8 will be swung for actuating the corresponding link 14. By turning the shaft 5 properly, either lever 13 can be swung.

With the rollers in the position seen in Fig. 110

5, the cam when operated in one direction will swing one lever, and when operated in the other direction will swing the other lever, either lever when swung being returned to normal position when the cam is returned to normal position with the shaft 5.

A cap 16 is fitted over the upper end of the body 1 and its flange 4 and has its rim surrounding the flange. The cap 16 is provided with a central upstanding boss 17 embracing the shaft 5, and secured thereto by means of a rivet 18 or other suitable securing element, whereby the shaft 5 turns with the cap. This cap 16 sheds water and sleet, and thereby protects the parts underneath it. A web portion 19 extends radially from the boss 17 and upwardly from the cap 16, and is provided with a downwardly and outwardly opening recess 20, the portion 19 having a tongue 21 projecting therefrom over the outer end of the recess 20 to extend over a lock (not shown) which is disposed at the outer end of the recess 20. An operating lever 22 is pivoted, as at 23, to the portion 19 within the recess 20, and is provided at its pivoted end with an ear 24 extending at an angle therefrom and provided with an aperture 25. The flange 4 is provided at suitable points thereof with notches 26 into which the lever 22 can swing downwardly when the shaft 5 is brought to different positions for setting the switch or switches in the desired positions. When the lever 23 is swung upwardly, it is removed from the corresponding notch 26, and the lever can then be swung to rotate the shaft 5 in either direction. When the lever 23 is swung downwardly into anyone of the notches 26, the apertured end of the ear 24 is swung outwardly to project from the portion 19, and a padlock or other suitable lock can then be engaged with the apertured portion of the ear 24 to hold the lever 22 in the notch 26 and therefore prevent the operation of the switch stand unless a proper key is used for releasing the lock. The tongue 21 will extend over and shield the lock from above.

As a means for limiting the rotation of the shaft 5, a stop 27 is carried by the upper end of the body 1, said upper end of the body being provided with apertures or sockets 28 for the adjustable reception of one or more stops 27, to limit the movement of the lever 22. When the lever 22 is raised for rotating the shaft 5, the inner or upper end of the lever is swung downwardly against or adjacent to the upper end of the body 1, and as the lever 22 is swung, the same will strike the stop 27 when the lever is moved over one notch 26. Two of the stops 27 can be used, if desired, and the stops can be adjusted to different positions for limiting the movement of the shaft 5 according to the conditions. The cap 16 is

provided with an annular groove 29 for receiving the stop 27.

Suitable oil holes can be provided for lubricating the parts, one of them being indicated at 30 in the cap 16 for injecting lubricant to the shaft 5 where it extends through the upper bearing portion of the body 1.

From the foregoing, taken in connection with the drawing, it is believed that the advantages and attributes of the structure will be apparent without further description being necessary.

Having thus described the invention, what is claimed as new is:—

1. A switch stand embodying a body, a shaft journaled for rotation therein for operating a switch, a cap secured to the shaft and fitting over one end of the body, a lever pivoted to the cap for turning said cap and shaft and swingable into engagement with the body at various positions for locking said shaft, said end of the body having adjustable means under the cap for limiting the swinging movement of said lever when turning the shaft.

2. A switch stand embodying a body having an outstanding notched flange and an annular series of sockets at one end, a stop engageable in said sockets, a shaft journaled in the body for operating a switch, a cap secured to the shaft and fitting over said end of the body and flange, and a lever pivoted to the cap to swing into a notch of said flange and swingable out of said notch for turning the cap and shaft, the lever when swung out of the notch being engageable with the stop when the lever is turned to rotate the cap and shaft.

3. A switch stand embodying a body having a downwardly opening chamber, a vertical shaft journaled in the body and projecting downwardly into said chamber, a cam carried by the shaft within said chamber, and a bell crank lever having its elbow fulcrumed within said chamber having one arm engaging the cam to be swung upwardly and downwardly and having its other arm depending from said chamber to operate a switch.

4. A switch stand embodying a body having a chamber, a shaft journaled in said body and projecting into said chamber, a strip secured to the body across said chamber, a cam secured to said shaft within said chamber, and a bell crank lever having its elbow fulcrumed to said strip and having one arm engaging the cam, the other arm of the lever projecting from said chamber for operating a switch.

5. A switch stand embodying a body having a chamber, a shaft journaled in the body and projecting into the said chamber, a strip secured to the body across said chamber, opposite bearings carried by said strip

within said chamber, a cam secured to the shaft within said chamber, and a pair of opposite bell crank levers having their elbows fulcrumed to said bearings, one arm 5 of each lever engaging the cam, and the other arm projecting out of said chamber for operating a switch.

In testimony that I claim the foregoing as my own, I have hereunto affixed my signature in the presence of two witnesses.

JOSEPH PHILANDER HASTY.
